UNITED STATES PATENT OFFICE.

BERT G. DUNHAM, OF HAWTHORNE, NEW JERSEY, ASSIGNOR, BY MESNE ASSIGNMENTS, TO WESTERN ELECTRIC COMPANY, INCORPORATED, A CORPORATION OF NEW YORK.

TWO-WIRE MULTIPLE AUTOMATIC TELEPHONE SYSTEM.

1,339,175.

Specification of Letters Patent.

Patented May 4, 1920.

Application filed August 30, 1915. Serial No. 48,134.

To all whom it may concern:

Be it known that I, BERT G. DUNHAM, a citizen of the United States, residing at Hawthorne, in the county of Passaic and State of New Jersey, have invented certain new and useful Improvements in Two-Wire Multiple Automatic Telephone Systems, of which the following is a full, clear, concise, and exact description.

10 This invention relates to improvements in an automatic telephone system of the two-wire multiple type, such as shown in an application of Charles L. Goodrum, Serial No. 35,326, filed June 21, 1915 issued as Patent

15 No. 1,251,503, Jan. 1, 1918.

One of the objects of this invention is the provision of a system, in which the bridges containing the operating relays are not removed from the line after the establishment

20 of a connection.

Another object of the invention is the provision of a repeating relay at a selector switch by means of which the controlling impulses for operating the succeeding

25 switches are relayed over one of the talking conductors.

Figures 1, 2 and 3 of the drawings, with Fig. 1 at the left and Figs. 2 and 3 following in order, show the circuits of the invention

30 and diagrammatically indicate the apparatus employed therein.

Any step-by-step two-movement switch may be employed with the circuits shown. A switch of this general character is shown

35 in a patent to Keith and Erickson No. 815,175, although a switch such as disclosed in an application of Charles L. Goodrum, Serial No. 872,743, filed November 18, 1914, will preferably be employed. Of course, it

40 is to be understood that in practising this invention only two brushes will be employed on each switch, and the stationary contacts will be correspondingly reduced in number.

Although the invention is disclosed in a

45 system using step-by-step switches, certain features thereof are applicable to systems employing other types, as power-driven switches.

With each switch is associated a circuit-

50 changing device for controlling certain operating circuits at its respective switch. Such devices may be of the general character of the switch shown in the above men-

55 tioned patent and referred to therein as a side switch. A circuit controlling switch, such as will preferably be employed in the present invention, is shown in the above mentioned Goodrum application. Such a circuit controlling device may be caused to effect circuit changes, either by the de-

60 energization or the energization of its operating magnet as described in said applica-

tion.

The line finder switch and circuits shown

65 on Fig. 1 are substantially the same as dis-

closed in the Goodrum application above re-

ferred to, and, therefore, this part of the sys-

tem will be only briefly described.

As the circuits employed in this system are

70 of a very simple character, it is believed

that the invention will be readily understood

from the following description in which the

establishment of a successful and an unsuc-

cessful connection is described, and also the

75 manner of releasing the switches in either

instance.

We will assume that the subscriber shown

at the left in Fig. 1 of the drawings desires

to establish a connection with the subscriber

shown to the right in Fig. 3. Upon remov-

80 ing his receiver from the hook, a circuit is

completed through line relay 1 which, in

attracting its armature, completes a circuit

from battery through relay 2, left back con-

85 tact of relay 3, left back contact of test

relay 4, left contact of relay 1, and right

winding of relay 1 to ground. Relay 2 pulls

up and completes a locking circuit through

its left armature. A circuit is now com-

85 pleted from battery through rotary step-

ping magnet 5, side switch wiper 6, back

contact of release magnet 7, relay 3, inner-

most right armature and front contact of

relay 2, and right armature of relay 4 to

90 ground. Due to the individual interrupter

associated with the magnet 5, the switch

brushes are moved from group to group of

the line contacts until the rotary test brush

95 8 engages the contact individual to the group

of the calling line, when a circuit is com-

pleted from battery through escape or side

switch magnet 9, side switch wiper 10, brush

100 8, to the group contact of the calling line,

armature and contact of relay 2, and arma-

ture and contact of relay 4 to ground. The

105 escape magnet 9 operates and moves the side

switch wipers to position 2.

In position 2, a circuit is completed from

battery through vertical stepping magnet 11, side switch wiper 6, contact and armature of release magnet 7 to ground at the right armature of relay 4. The switch brushes 12 5 and 13 are stepped from line to line until the terminals of the calling line are encountered, when a circuit will be completed from a source of current through test relay 4, right front contact of line relay 1, the upper 10 talking conductor of the line, line contact and brush 13, side switch wiper 14, the lower trunk conductor, condenser 15 and resistance 16 to battery and ground. Test relay 4 is energized and removes the ground from the 15 vertical stepping magnet circuit, thus stopping the movement of the switch. The escape magnet 9 was energized in parallel with the vertical magnet 11. Upon the operation of relay 4, it becomes deenergized, 20 moving the side switch wipers to position 3.

The calling line is now connected through the side switch wipers 14 and 17 to the first selector switch. A circuit now extends from battery through resistance 16, the lower 25 trunk conductor, side switch wiper 17, brush 12 and cut-off relay 18 to ground. Relay 18 is operated and removes the subscriber's line from connection with the line relay 1.

When side switch wiper 17 moves into the 30 third position, busy potential is supplied to the multiple contacts associated with the brush 12 through resistance 16. The apparatus is now in condition for the receipt of the controlling impulses at the first selector 35 shown at the left in Fig. 2.

The calling subscriber now works his dial to operate the line relay 19 at the first selector. The operating circuit may be traced from battery through resistance 16, the 40 lower trunk conductor, left side of the calling subscriber's line, the substation and the calling device thereat, the right side of the subscriber's line, upper trunk conductor and through relay 19 to ground. Upon the first 45 energization of relay 19, a circuit is completed from ground, armature and front contact of said relay, rotary off-normal contact 20, back contact of rotary stepping magnet 21, side switch wiper 22 and the escape magnet 23 to battery and ground. The escape magnet is made slow to release, and consequently holds up during the series of impulses. On the first deenergization of the line relay, a circuit is completed from ground 50 through its armature and back contact, armature and front contact of escape magnet 23, side switch wiper 24, and rotary magnet 21 to battery and ground. The rotary magnet is energized with each deenergization of 55 the line relay 19. With the first rotary step, the rotary off-normal contact spring 20 separates from its upper contact and engages its lower contact, and through the remaining impulses of the series the magnet 23 is maintained energized at the back contact of relay 60 65

19. At the termination of the series of impulses, relay 19 remains energized and the escape magnet 23 falls off, moving the side switch wipers to position 2.

A circuit now extends from battery 70 through vertical stepping magnet 26, side switch wiper 25, back contact of test relay 27 and front contact of line relay 19 to ground. The brushes 28 and 29 are moved from trunk to trunk by the repeated energization and deenergization of the magnet 26 brought about by means of its individual interrupter 30. When the contacts of an idle trunk of the group are encountered, a circuit is completed from battery through test 80 relay 27, brush 29, conductor 31, rotary off-normal contact 32, back contact of escape magnet 33, and back contact of line relay 34 to ground. Relay 27 is energized and interrupts the circuit for magnet 26, thus stopping 85 the movement of the brushes and closes a circuit from battery through escape magnet 23, wiper 22, front contact of relay 27, and front contact of relay 19 to ground. Magnet 23 is energized and causes the side 90 switch wipers to move into position 3.

In position 3, circuits are completed for line relay 34 and for relay 36 as follows: from battery through relay 34, brush 28, side switch wiper 37, back contact of relay 95 36 to ground, through front contact and armature of relay 19. Another circuit is completed from battery through relay 36, side switch wiper 38, front contact of test relay 27 to ground through contact and armature of relay 19. As relay 36 is made slow to pull up, relay 34 becomes energized and interrupts the circuit for test relay 27, which falls off before relay 36 has attracted 100 its armature. Upon the energization of relay 34, a circuit is completed from battery through relay 33, side switch wiper 39, contact and armature of rotary stepping magnet 40, rotary off-normal contact 41, and front contact and armature of relay 34 to 110 ground. Relay 33 energizes, and as it is made slow to release it remains energized throughout the series of impulses.

We are now ready for sending the impulses to the second selector switch. The 115 impulses for the second selector switch and the connector are relayed by means of line relay 19. Upon sending the impulses, the relay 19 is repeatedly energized and deenergized as occurred when the first selector 120 switch was operated. Upon each energization of said relay, a circuit is completed from ground through armature and front contact of relay 19, back contact and armature of relay 36, and line relay 34 to battery 125 and ground. Thus relay 34 will be energized with each energization of relay 19 and deenergized with each deenergization of relay 19. With each deenergization of relay 34, a circuit is completed from battery 130

through rotary stepping magnet 40, side switch wiper 45, front contact and armature of relay 33, and back contact and armature of relay 34, to ground. Thus, by means 5 of the impulses transmitted from the calling subscriber's station, the brushes 47, 48 are stepped from group to group of the trunks leading to final connectors, such as shown in Fig. 3. With the first rotary impulse, 10 the off-normal contact 41 opens at its upper contact and closes at its lower one, so throughout the succeeding impulses of the series the relay 33 is maintained energized at the back contact of relay 34. At the 15 termination of this series of impulses, the relay 34 remains energized and the relay 33 falls off and interrupts the previously established circuit from battery through escape magnet 42, wiper 43, wiper 51, right 20 contact of relay 33, and back contact of relay 35. Magnet 42 retracts its armature and moves the side switch wipers into position 2.

A circuit is now completed from battery 25 through the vertical stepping magnet 49, its individual interrupter contact 50, wiper 51, front contact and armature of relay 33, and back contact and armature of relay 35 to ground, relay 33 having been 30 energized by the closure at wiper 39 in its second position of the following circuit; grounded battery, relay 33, wiper 39, front contact and armature of relay 34 to ground. By means of its individual interrupter, the 35 magnet 49 is repeatedly energized and de-energized, thus stepping the switch brushes over the busy trunks of the group with which they are now associated.

When an idle trunk is found, a circuit is 40 completed from battery through test relay 35, the upper trunk conductor, conductor 52, rotary off-normal contact 53, back contact and left armature of relay 54, and back contact and armature of relay 55 to ground. 45 Relay 35 is energized and interrupts the circuit for the vertical stepping magnet 49. It also closes a circuit from battery through the escape magnet 42 and wiper 43, and the side switch wipers move to position 3.

50 When the side switch moves to position 3, a circuit is completed from battery through line relay 55, lower trunk conductor, side switch wiper 44, wiper 37, armature and back contact of relay 36 to ground, through 55 front contact and armature of relay 19. Relay 55 in pulling up interrupts the circuit for the test relay 35, which becomes de-energized. A circuit is also completed from battery through slow-release relay 54, side 60 switch wiper 58, armature and contact of rotary magnet 59, rotary off-normal contact 60, and front contact and armature of relay 55 to ground. The energization of relay 54 completes a circuit from battery through 65 slow-release escape magnet 61, contact and

right armature of relay 54, back contact and armature of relay 62, and back contact and armature of relay 63 to ground.

The subscriber now works his sending device, causing the repeated energization and 70 deenergization of line relay 19, which, as before, grounds the lower side of the line with each energization and removes said ground with each deenergization. With each deenergization of relay 19, relay 55 75 becomes deenergized and completes a circuit from battery through rotary stepping magnet 59, wiper 64, front contact and armature of relay 54, and back contact and armature of relay 55 to ground. The connector switch 80 brushes are, therefore, stepped from group to group of the contacts of the lines terminating therein. With the first rotary impulse, contact 60 separated from its upper contact and engaged its lower one, and 85 through the remaining impulses of the series the relay 54 is maintained energized through said off-normal contact 60 and back contact of relay 55.

Upon the termination of the impulses of 90 the series, however, relay 54 becomes deenergized and in turn interrupts the circuit for the escape magnet 61, causing the side switch to move to position 2. A circuit now extends from battery through relay 54, wiper 58, armature and contact of magnet 65, vertical off-normal contact 66, front contact and armature of relay 55 to ground. The units series of impulses are now transmitted by the calling subscriber, 95 causing the repeated energization and de-energization of the relay 55 in a manner now well understood. With each deenergization, a circuit is completed from battery through vertical stepping magnet 100 65, side switch wiper 64, front contact and armature of relay 54, back contact and armature of relay 55 to ground. With the first vertical step, contact spring 66 disengages its upper coöperating contact and engages 110 its lower one, and throughout the remaining impulses of the series the relay 54 is maintained energized through the back contact of relay 55.

When the switch brushes stop on the terminals of the desired line, a circuit is completed from ground through right winding of relay 67, back contact and armature of relay 68 to the lower connector switch brush and contact engaged thereby. If the called 115 line is busy, battery potential will be upon this contact. If the line is busy as a calling line, this current will be supplied through resistance 16 at the first selector. If busy as a called line, the busy potential will be supplied through relay 68 at the connector switch. 120

Assuming first that the called line is idle, the escape magnet will release its armature causing the side switch wipers to move to 130

position 3, thus completing a circuit from battery through ringing relay 68, side switch wiper 69, the lower brush of the switch and contact engaged thereby, and 5 cut-off relay 18' to ground. Relay 68 attracts its armature and completes a circuit from a source of ringing current through ringing trip relay 62, front contact and armature of relay 68, side switch wiper 70 over the called subscriber's line, through the 10 signaling device thereof, and back to ground through relay 18'. If the called subscriber responds, relay 62 will become energized due to the increased flow of current.

15 When the side switch went to position 3, a circuit was completed from battery through relay 54, side switch wiper 58, and front contact and armature of relay 55 to ground. Relay 54 in turn completed a circuit from 20 battery through escape magnet 61, contact and armature of relay 54, back contact and armature of relay 62 to ground, through contact and armature of relay 63. When the trip relay 62 attracts its armature, it 25 rupts the last traced circuit causing the side switch to move to position 4.

In position 4, a circuit is completed from ground through left winding of relay 67, side switch wiper 71, conductor 52, upper 30 trunk conductor and relay 27 to battery and ground. Relay 27 pulls up and completes a circuit from battery through relay 36, wiper 38, front contact of relay 27, and front contact of relay 19 to ground. Relays 67 35 and 36 being energized, the connection is now complete through to the line of the called subscriber. When relay 27 was energized, relay 35 also became energized over a parallel circuit and completed a circuit 40 from battery through relay 33 and wiper 39. This holds relay 33 energized and the circuit for release magnet 73 open.

The release of the finder switch and first selector switch is now under the control of 45 the calling subscriber, while the release of the second selector switch and the connector switch is under the control of the called subscriber. When the side switch moved into position 4, relay 63 was energized by current supplied over the subscriber's line from battery at relay 68. Relay 63 in turn completed a circuit from battery through relay 54, wiper 58 and the armature and contact of relay 63. Therefore, the circuit of the 55 release magnet 72 is maintained open at the left armature and back contact of relay 54 as long as the called subscriber's circuit is closed. The circuit for the release magnet 73 of the second selector is maintained open 60 at the back contact of relay 33.

When the called subscriber replaces his receiver on the hook, relay 63 becomes de-energized and interrupts the circuit for relay 54. Relay 54 retracts its armature and 65 completes a circuit from battery through

release magnet 72, off-normal contact 53, back contact and armature of relay 54, and back contact and armature of relay 55. Relay 55 was deenergized when relay 36 pulled up and removed ground from the lower 70 trunk conductor. Magnet 72 upon energization closes a locking circuit for itself through its armature 74, so that it will be maintained energized until off-normal contact 53 is opened when the switch reaches its 75 normal position.

As the side switch returns to its normal position wiper 71 removes ground from the upper trunk conductor, causing relay 35 to become deenergized. This interrupts the 80 circuit of relay 33, which falls off and closes a circuit from battery through the winding of release magnet 73, off-normal contact 32, back contact and armature of relay 33, and back contact and armature of relay 34. Release magnet 75 is energized and completes 85 a locking circuit for itself in the same way as did magnet 72.

Turning now to the first selector, it will be noted that the slow-release magnet 23 90 has been maintained energized during conversation, and indeed at all times since the side switch wiper went into the third position, by a circuit extending through the front contact of relay 19. Now when the 95 calling subscriber replaces his receiver upon the hook, the circuit for relay 19 is interrupted and it releases its armature, thus interrupting the circuit for the magnet 23 which retracts its armature. Circuits are 100 now completed from battery through the release magnets 7 and 75 in parallel through the rotary off-normal contact 76, back contact and armature of relay 23, back contact and armature of relay 19 to ground. Release magnets 7 and 75 are energized and 105 return the finder switch and the first selector switch to their normal positions.

We will now consider an unsuccessful call. It will be remembered that at the time the 110 connector switch brushes made connection with the terminals of the wanted subscriber's line, the side switch was in position 2. If the line is busy, the lower or test terminal of the line in Fig. 3 will be of 115 raised potential, as hereinbefore described, and current will flow from said terminal through the lower switch brush, armature and back contact of relay 68, and the right winding of relay 67 to ground, energizing 120 relay 67. As the escape magnet 61 is slow to release, it has held up during this operation, and a holding circuit is now provided therefor which extends through side switch wiper 69, contact and left armature of test 125 relay 67, side switch wiper 71 and the left winding of relay 67, thus maintaining the side switch in position 2. Relay 67 at its right armature and front contact connects the busy tone device 77 to the upper con- 130

ductor of the trunk, thus causing a tone to be transmitted to the calling subscriber to indicate to him that the wanted line is busy. Relay 68 will be energized by a circuit extending through the contact and left armature of relay 67, wiper 71 and left winding of relay 67; but as the side switch is still in position 2, the ringing circuit will be open at side switch wiper 70. The calling subscriber 10 hearing the busy tone will replace his receiver on the hook, causing the release of the finder switch and the first selector in the manner hereinbefore described. When relay 19 retracts its armature, ground will be 15 removed from the lower trunk conductor, and relays 34 and 55 will become deenergized.

As relay 35 is deenergized at this time, the energizing circuit for relay 33 is controlled 20 at the front contact of relay 34. Therefore when relay 34 retracts its armature, relay 33 also falls off, and a circuit is completed from battery through release magnet 73, off-normal contact 32, back contact of relay 33 25 and back contact of relay 34. Magnet 73 pulls up and completes a locking circuit for itself as before described. The armatures of relay 54 will be back at this time, and when relay 55 retracts its armature a circuit will 30 be completed from battery through release magnet 72, off-normal contact 53 and back contacts of relays 54 and 55, causing magnet 72 to pull up and lock. When relay 55 retracted its armature, it also completed a 35 circuit for relay 54, but magnet 72 will have operated and locked up before relay 54 will open the energizing circuit therefor.

Associated with each of the stepping magnets of the selector switches and of the connector switch, by means of which directive movement is imparted to said switches, is an armature contact device, by means of which the switch is prevented from being tied up if the calling subscriber replaces his 45 receiver on the hook while a series of impulses are being transmitted.

Referring first to the first selector (at the left in Fig. 2), it will be remembered that at the time the series of impulses are transmitted 50 to effect the rotary movement of this switch, the side switch is in position 1. If now, after a certain number of impulses have been transmitted, but before the switch has had time to hunt for and select an idle 55 trunk in the selected group, the substation circuit of the calling subscriber is interrupted, the line relay 19 will retract its armature and will remain back. After the first rotary step, the escape magnet 23 is 60 maintained energized by a circuit extending through side switch wiper 22, contact and armature of rotary magnet 21, off-normal contact spring 20 and its lower contact, and the back contact of line relay 19. Thus it 65 will be seen that if it were not that this cir-

cuit was carried through the armature of stepping magnet 21, the escape magnet would remain energized and the switch would, therefore, be tied up. However, when the line relay retracted its armature, 70 it completed a circuit for the rotary magnet 21, as previously described, causing it to open and maintain open the circuit of the escape magnet 23, which, after a brief interval, would fall off and complete the circuit 75 for the release magnet 75. The same provision is made at the second selector, and it is thought its operation will be readily understood from the foregoing description.

A similar expedient is also employed in 80 association with both the stepping magnets of the connector switch, and it is thought that the manner in which the release is effected in the connector will also be readily understood from the description of the release of the first selector switch. 85

It will be noted that in the present system there is a portion of the talking circuit included between the condensers at the left in Fig. 2 and those at the left in Fig. 3 over 90 one of the conductors of which the repeating impulses are transmitted from the relay 19, and over the other of which the test is accomplished. This permits the provision of operating circuits wherein the relays and 95 magnets associated with the conductors in establishing a connection need not be cut off during conversation, as it has been found that if the relays branched off from the conductors included between the condensers before mentioned are of relatively high resistance and impedance, the loss of voice currents is so slight as to be negligible. 100

In the present system, it will be noted that the operating impulses for the stepping relays are transmitted over one of the talking conductors, and that the release and the test, with the exception of that of the connector, takes place over the other talking conductor. 105

It is obvious that many modifications of the present invention may be devised without departing from the spirit thereof. Applicant therefore desires it understood that the invention is to be limited merely by the 110 scope of the claims.

What is claimed is:

1. In a telephone exchange system, a selector switch, conductors extending to said switch, means for receiving selecting impulses sent according to a predetermined code joined to one of said conductors, a source of current, and a testing device at said switch permanently connected to said source and to the same conductor. 115

2. In a telephone exchange system, a selector switch, conductors extending to said switch, means for receiving selecting impulses sent according to a predetermined code joined to one of said conductors, and 120 125 130

a testing device at said switch connected to an inductively associated portion of the same conductor.

3. In a telephone exchange system, a selector switch, conductors extending to said switch, means for transmitting impulses over said conductors to said switch, impulse receiving means connected to one of said conductors and arranged to be operated by every impulse transmitted over said conductors, release means controlled by said impulse receiving means, and test means connected to the same conductor.

4. In a telephone exchange system, a selector switch, talking conductors extending to said switch, means for transmitting impulses over said talking conductors to said switch, impulse receiving means connected to one of said talking conductors and arranged to be operated by every impulse transmitted over said talking conductors, release means controlled by said impulse receiving means, and test means connected to the same talking conductor.

5. In a telephone exchange system, a selector switch, talking conductors extending thereto, test means permanently connected to one of said talking conductors, and release means connected to the same conductor.

6. In a telephone exchange system, a switch, a pair of conductors extending to said switch, a stepping relay permanently connected to one of said conductors, a source of current, and a release-controlling relay permanently connected to said source and to the other said conductor, said controlling relay being arranged to also determine the busy or idle condition of the wanted line.

7. In a telephone exchange system, a switch, a pair of talking conductors extending to said switch, a stepping relay permanently connected to one of said conductors, a source of current, and a release-controlling relay permanently connected to said source and the other said conductor, said controlling relay being arranged to also determine the busy or idle condition of the wanted line.

8. In a telephone exchange system, a switch, a pair of conductors extending thereto, means for transmitting impulses over said conductors to said switch, a stepping relay connected to one of said conductors and arranged to be operated by every impulse transmitted over said conductors,

releasing means controlled by said stepping relay, and a test relay connected to the same conductor.

9. In a telephone system, a connector or final switch, a pair of talking conductors extending to said switch, a stepping relay at said switch for controlling the setting thereof permanently joined to one of said conductors, a second relay permanently joined to the other said conductor, release means for said switch controlled by said first mentioned relay prior to the response of the called subscriber, and means whereby said release means is controlled solely by said second relay subsequent to such response.

10. In a telephone system, a connector or final switch, a pair of talking conductors extending to said switch, a stepping relay at said switch for controlling the setting thereof permanently joined to one of said conductors, a second relay, through which talking current is supplied to the called subscriber, permanently joined to the other said conductor, release means for said switch controlled by said stepping relay prior to the response of the called subscriber, and means whereby said release means is controlled solely by said second relay subsequent to such response.

11. In a telephone exchange system, a switch, a pair of conductors extending thereto, means for transmitting impulses over said conductors to said switch, a stepping relay connected to one of said conductors and arranged to be operated by every impulse transmitted over said conductors, a test relay connected to the same conductor, and a release controlling means connected to the other conductor.

12. In a telephone exchange system, a switch, a pair of talking conductors extending thereto, means for transmitting impulses over said talking conductors to said switch, a stepping relay connected to one of said talking conductors and arranged to be operated by every impulse transmitted over said talking conductors, a test relay connected to the same talking conductor, and a release controlling means connected to the other talking conductor.

In witness whereof I hereunto subscribe my name this 26th day of August, A. D. 1915.

BERT G. DUNHAM.
